UNITED STATES PATENT OFFICE

JOSEPH H. COPE, OF DENVER, COLORADO

EXTENSION HAYSTACKER

Application filed January 16, 1928. Serial No. 247,179.

This invention relates to improvements in hay stackers of the type in which the hay is deposited onto a stacker head and then elevated and deposited onto the stack by means of power. It is the object of this invention to improve the construction of stackers of this type so as to obtain better operation and to simplify and strengthen the construction.

It is the further object of this invention to produce a stacker of this type that shall have an improved pull-back which will also act as a stop for limiting the overthrow of the stacker head.

It is the further object of this invention to improve the construction of the truck so that the frame will be automatically raised whenever the stacker head is lowered and which will automatically latch the truck in operative position so that the stacker head can be raised for the purpose of passing through gates and for other reasons.

It is a still further object of this invention to provide improved guides for the cables that will positively prevent the cables from falling off from the pulleys when the stacker is in operation.

The above and other objects which will become apparent as the description proceeds are obtained by means of a construction and an arrangement of parts that will now be described in detail, reference for this purpose being had to the accompanying drawings, in which the construction has been illustrated, and in which:

Fig. 1 is a top plan view of my improved stacker showing the same in its normal position;

Fig. 2 is a side elevation of one of the wheels of the truck, looking in the direction of arrow 2, Fig. 1;

Fig. 3 is a section taken on line 3—3, Fig. 2; Fig. 4 is a section taken on line 4—4, Fig. 2;

Fig. 5 is a section taken on line 5—5, Fig. 1; Fig. 6 is a side elevation of my improved stacker;

Fig. 7 is a view looking in the direction of arrow 7 in Fig. 8, and shows a detail of the construction;

Fig. 8 is a section taken on line 8—8, Fig.

9 and illustrates the construction of one of the cable guides;

Fig. 19 is a section taken on line 19—19, Fig. 18;

Fig. 20 is a section taken on line 20—20, Fig. 18;

Fig. 21 is a section taken on line 21—21, Fig. 18;

Fig. 22 is a side elevation showing a slightly modified form of latching mechanism; and

Fig. 23 is a section taken on line 23—23, Fig. 22.

My improved stacker is supported on a frame comprising side pieces 1, 1, which are connected by transverse pieces 2. Extending upwardly from one end of this frame are corner posts 3. These corner posts are held in upright position by means of a transverse bar 9 that extends between the tops of these posts and is connected to the center post 40, and

by inclined brace members 5, whose lower ends are mortised into the side members 1 in the manner shown in Fig. 18. From Fig. 18, it will be observed that the upper edges of side members 1 are provided with transverse notches 6 and the lower ends of the inclined brace members 5 are provided with downwardly extending projections 7 that fit into

these notches. Bolts 8 pass through the low-

55

60

65

70

75

100

er ends of the brace members 5 and through the side members 1 so as to clamp the parts together. Referring now to Fig. 5, it will be observed that the upper ends of the braces 5 terminate adjacent the transverse bar 9 and that they are located between the two spaced corner posts 3. A metal strap 10 is secured to the underside of each brace 5 and has its end 11 located under the under surface of the transverse bar 9 to which it is secured by means of a bolt 12. A corresponding metal strap 13 is secured to the upper side of each brace and this, together with the strap 10, is held in place by means of bolts 14. The upper ends of straps 13 have transverse portions 15 that extends over onto the rear surfaces of the corner post 3 and are secured to the latter by means of bolts 16. By properly locating strap 13, it is obvious that it can be put under considerable tension by tightening the bolts 16 and by this means a very solid joint is obtained. Attention is called at this point to the fact that any force tending to move the corner post outwardly along the length of the frame is resisted by the braces 5 and that this force is transmitted to the side bars 1 by means of the downward projection 7 and the sides of the transverse notches 6. The lower ends of the braces 5 are also connected to the side members 1 by means of straps 17. Attention is called at this point to the fact that each of the brace members 5 are provided with notches 18 on their under surfaces, Fig. 18.

Secured to each side of the frame are two parallel bars 19 which perform the double function of stops and pullbacks in a manner which will be hereinafter more fully described. One of these bars is located to each side of the brace members 5 in the manner shown in Figs. 1 and 19. These bars are held together by means of bolts 20 and are held in spaced relation by means of ferrules 21. The lower ends of each pair of combined stop and pullback bars is connected to the lower ends of the corresponding corner posts by means of straps 22, one end of which is pivoted to the lower bolt 20 and the other of which is pivoted to the bolt 23 that connects the corner posts to the side bar 1. A spring 24 has its lower end connected to a bracket 25 that is secured to the brace 5 and its upper end connected to a bracket 26, which is attached to the bars 19, Fig. 18. The transverse bolt 20 which is located above the place where the links 22 are pivoted, is so positioned that when the pullback bars are in their rearmost position, the ferrule 21 will engage the notch 18 and serve as a stop for limiting the rearward movement of these bars.

Attention is called at this point to the brace 27 that extends from the lower side of each brace 5 to the upper edge of the corresponding side bar 1 in the manner shown in

Figs. 6 and 18. This brace is connected with the side bar in the same manner as described in connection with the lower end of brace 5, and the parts have therefore been given corresponding numbers. For the purpose of 70 bracing the supporting frame so as to keep it in its rectangular form, diagonal brace bars 28 are provided at each end, in the manner shown in Fig. 1. Pivoted to the side bars 1 by means of bolts 29 is an A frame, 75 comprising two side members 30 that are connected by means of parallel transverse members 31. The upper ends of these side bars 30 are connected by means of a bolt 32 on which is pivoted the grooved pulley 33. 80 The upper ends of the flat steel bars 34 are also secured to the bolt 32. A cable guide 35 which is formed of a piece of sheet metal having parallel sides 36 that embrace the pulley 33 is also pivotally secured to the bolt 32. This cable guide is provided with holes 37 through which the cable 38 passes, and also with a hole 39 to which the end of the cable is anchored in the manner shown in Fig. 8.

Referring now more particularly to Figs. 10 and 11, it will be observed that I have secured to the center post 40 two spaced grooved pulleys 41 and 42. These pulleys are located between the side bars 43 and the latter are 90 secured to the upper end of post 40 by means of side straps 44, whose upper ends are perforated for the reception of the bolt 45 which serves as a pivot for the pulley 42. Another strap 46 is connected to the upper end of post 40 by means of a bolt 47 and has its upper end perforated for the reception of the bolt 48, which serves as a pivot for pulley 41. A cable guide 35 which is constructed like the one described in connection with Fig. 8 is pivoted to the bolt 48 and cooperates with the pulley 41 to direct the cable 38 into the groove of this pulley. A slightly different form of cable guide has been indicated by numeral 49 and cooperates with the pulley 42 in the manner shown in Fig. 10. Inclined metal bars 50 extend from the upper end of post 40 to the side members 1 and serve to hold this post against sidewise movement. For the purpose of further bracing the post 40, I have provided diagonal braces 51 that extend from the upper end of the post to the side members 1 and have their lower ends secured to the latter by means of bolts 52. It will be apparent from the above that post 40 is very securely braced against movement with respect to the frame and that it therefore serves as a rigid anchor for pulleys 41 and 42 with which the cable 38 is operatively associated. The stacker head which comprises a plurality of teeth 53 that are connected to each other by means of transverse bars 54 and a plurality of vertically extending teeth 55, which are likewise connected to each other by means of a transverse 100

90

100

105

110

115

120

125

130

bar 56, is secured to the ends of two parallel arms 57. Diagonal braces 58 extend from the vertical teeth 55 to the horizontal teeth 53 and hold these two sets of teeth in a predetermined relation. The arms 57 are connected by means of transverse bar 54 and rest upon two parallel arms 60 which are pivoted to the diagonal braces 5 at 61. Arms 60 are connected by means of transverse bars 59 and 62 which holds them in spaced relation. The arms 57 are provided near their ends with hoops 63 which enclose the side arms 60 and are slidable along the latter. Secured to the upper surface of the transverse bar 62 are Z-shaped guides 64 whose lower ends are secured to the transverse bars by means of bolts 65 and whose upper ends 66 are bent so as to project over the arms 57, Fig. 15. Rods 67 have their lower ends 68 extending through openings in the guide members 64 and in the arms 60 and are held in place by means of nuts 69. The upper ends of these rods are secured to the lower ends of the straps 34 in the manner illustrated in Fig. 7. The connection between strap 34 and bar 67 may be effected in any suitable way but has been shown in the following manner. The lower end of each bar 34 has been bent outwardly in the manner indicated by numeral 68. These outwardly bent ends are perforated and the bars 67 are passed through the openings in these outwardly bent ends. The upper ends of rods 67 are bent inwardly as indicated by reference numeral 69 so as to form hooks which extend through openings in the bars 34. In this manner a good and substantial connection is made without the use of bolts or rivets. It is now apparent that the A frame comprising the side members 30, has its upper end connected with that part of the lifting frame comprising the side members 60 by means of bars 34 and rods 67, and therefore when the A frame is rotated in a clockwise direction, from the position shown in Fig. 6, it will also rotate the lifting frame and the attached extension frame together with the stacker head and finally bring the parts into the position shown in Fig. 12. As the stacker head usually carries a load of hay, it is apparent that considerable power is required to raise the same. And this is provided by a tractor, or by a team of horses. The cable 38 has been shown as having one end anchored to the cable guide 35 at the top of the A frame and as extending about the pulley 41 thence returning and passing around the pulley 33 from which it extends to the pulley 42. From the pulley 42, cable 38 extends downwardly in front of the upright 40 and passes around the pulley 70, which is pivotally connected to the frame by means of the bracket 71 and the plate 72 in the manner shown in Fig. 13. When the cable is pulled in the direction of the arrow in Fig. 13, the A frame

will be rotated about its pivot and the stacker head raised and moved to the position shown in Fig. 12. It is apparent that some means must be provided to stop the movement of the stacker head and to assist in returning it after the tension in the cable has been removed. It is further necessary to provide means for extending the stacker head lifting frame so that the hay can be raised to the top of the stack as the latter is increasing in height. In order to accomplish the result just mentioned, I have provided pusher arms or links 73 whose upper ends are pivoted at 74 between the upper ends of the corner posts 3. The lower end of each pusher bar is provided with a guide and bracket 75 that has an end portion 76 which extends down along the outside of arms 57 and 60 and has its extreme lower end bent underneath bar 60 in the manner shown most clearly in Figs. 18 and 20, and indicated by reference numeral 77. A corresponding guide member 78 is secured to the other side of each pusher bar 73 but extends merely a short distance down onto the arm 57 in the manner shown in Fig. 20. These guide members serve to hold the ends of the pusher bars in proper relation to the stacker head lifting frame. The part 76 is provided with a notch 79 which is so located that it will engage a pin or bolt that is placed in holes 80 in each of the arms 57. When pins are placed in any of the holes 80 it is apparent that these pins will engage the notch 79 as the stacker head is moved upwardly and as soon as this occurs the arms 57 will be forced to slide along arm 60 to an extent determined by the position of the pins 81, in the manner quite clearly apparent from Fig. 12. From Fig. 18 it is apparent that when the stacker head occupies its lowermost position, that the guide 76 comes between the strap 63 and the first hole 80 and therefore if the pin 81 is placed in this hole, the stacker head will have the maximum extension, and therefore this extension can be varied by varying the position of the pins in the manner above indicated. A bracket 82 is secured to the upper side of each pusher bar 73 and is provided with an outwardly extending projection 83 that is so located that it will engage the uppermost bolt 20 in the stop and pullback bars 19, whenever the stacker head is moved to the position shown in Fig. 12. By referring to Fig. 6, it will be observed that since the pusher bars 73 are rotated about the pivots 74 and since the distance from the pivot 74 to the projection 83 is slightly less than the distance from this same pivot to the uppermost bolt 20 in the pullback bars 19, the projections 83 will engage underneath the bolts 20 as above mentioned. Upon further movement of the stacker head the pull back bars 19 will be raised, owing to the fact that the bolt 20 to which reference has been made will now be

rotating about pivot 74. This rotation and upward movement of bars 19 will continue until the parts are in the position shown in Fig. 12 in which position the bars 19 will engage with the upper ends of the corner posts 3 so as to stop the parts from further movement. During this movement, spring 24 has been extended in the manner clearly shown in Fig. 12 and when the parts have reached their maximum movement, this spring will be under considerable tension, and will therefore exert a force which together with the weight of the bars 19 tends to return the stacker head and the bars 19 to the position shown in Fig. 6. It is apparent from the description just given, that bars 19 form a two-fold function and serve as stops and also as means for pulling the parts backwards towards their starting position. 20 These bars have therefore been referred to as combined stops and pull back bars.

Whenever the stacker is to be transported, it is desirable that one end at least shall be supported on wheels and I have therefore provided a truck which consists of two wheels 84, one of which is located on each side of the supporting frame. Each wheel is mounted in a frame work having two parallel side members 85 and 86, to which the wheel is pivotally attached by means of a pivot pin 87. These frames are pivotally attached to the side members 1 at 88. The side 86 projects rearwardly so as to provide an extension 89 that is adapted to pass over the inclined head 90 of the bolt 91, which serves to latch it in the position shown in Fig. 2. A pin 92 serves as a stop which limits the downward movement of the frame. Secured to the transverse end portion 93 of the frame that encloses the wheel, is an arm 94 that is provided with an end portion 95 that extends at right angles to the arm and passes through an opening in the upwardly extending lug 96. This arm can be rotated about the axis of the part 95 so as to occupy a position like that shown in Figs. 3 and 4. When arm 94 is in the position shown in Fig. 3, it extends over the upper edge of the side member 1 and will be engaged by the bar 60 of the lifting frame 50 when the latter is moved from the position shown in Fig. 12 to that shown in Fig. 2. As the arms 60 come in contact with arms 94, the weight of the stacker frame and the stacker head will overbalance the weight of the supporting frame, which will therefore be raised upwardly from the position shown in Fig. 12 to that shown in Fig. 2. The weight of the stacker frame is sufficient to force the end 89 over the inclined head 90 into the position shown in Fig. 4, in which position the frames supporting the wheels will be latched so that if it is necessary the stacker frame can be raised a short distance without fear of having the supporting frame come in contact 60 with the ground. During normal operations

the arms 94 are thrown outwardly into the position shown in Fig. 6, and the supporting frame then rests on the ground along its entire length. Stops 97 secured to arms 57 are so located that they will be engaged by the guides 76 for pulling the stacker head back to the position shown in Fig. 6.

In Figs. 22 and 23 I have illustrated a slightly modified construction in which the stationary latching pin 91 has been replaced by a loop 91^a that encloses the side bar 1 and is slidable therealong from the full line to the dotted line position shown in Fig. 22. Loop 91^a has an inclined outward projection 90^a over which the extension 89 can slide and which serves to latch the latter in the position shown in Fig. 22. A stop 97 limits the movement of the loop in one direction while pin 92 limits it in the other direction. When the loop 90^a is in the dotted line position, it will be ineffective for latching the truck which will then be held in operative position by the weight of the lifting and the stacker head extension frames.

From the above description it will be apparent that I have produced an improved stacker mechanism of simple and substantial construction that is provided with a combined stop and pullback, which is positive in its action, and which greatly simplifies the construction and improves the operation. My improved construction is also very substantially braced and therefore will remain rigid and resist excessive strain better than constructions more poorly made.

Special attention is directed to the improved truck construction which is convenient and simple and which automatically latches in operative position so that the stacker head can be readily raised during transportation.

I desire to call particular attention to the arm 94 that is pivoted to the lug 96. In Fig. 6, this arm has been shown as thrown outwardly and this is the position that it occupies during the operation of the stacker. If it is desired to move the stacker then the operator throws arms 94 inwardly so that it rests upon the upper edge of bars 57 before the last load is raised. When the stacker lifting and extension frames are raised for the purpose of depositing the last load of hay on the stack, the arms 94 will fall into the position shown in Fig. 12 so as to project inwardly into such a position that they will extend into the path of the lifting frame and be engaged by it when the frame returns, thereby raising the front end of the supporting frame into the position shown in Figs. 2 and 22. The employment of means which, like arms 44, can be moved into a position in which they rest upon the extension arms 57 so as to drop into operative position when the stacker lifting frame is raised, simplifies the operation as it obviates the necessity of rais-

ing the frames for the special purpose of putting arms 94 into place.

I also desire to call particular attention to the means employed for pivoting the ends of the lifting frame bars 60 to the braces 5. This is accomplished by securing a flat metal bar to each side of the rear ends of bars 60 and extending the ends beyond the ends of the bars a sufficient distance to permit them to be secured to the braces 5 by means of bolts 61. By this simple construction the length of bars 60 can be made shorter and it is also possible to employ single braces instead of double braces such as are usually employed where the side bars are pivoted directly to the braces 5.

Having described the invention what I claim as new is:

1. A stacker comprising, in combination, a supporting frame having a rigid vertical corner post, a stacker head lifting frame having one end pivoted to the supporting frame, a stacker head carried by the stacker head lifting frame, means for rotating the stacker head lifting frame about its pivot, a combined stop and pullback bar, means for attaching the lower end of said bar to the corner post, said means comprising a link having one end pivoted to the lower end of the bar and the other end pivoted to the corner post, the upper end of the pull back bar lying in the path of movement of the lifting frame, a stop for limiting the movement of the pull back bar in one direction, and means comprising a spring for producing a force tending to move the bar towards the stop.

2. A stacker comprising, in combination, a supporting frame, a stacker head lifting frame having one end pivoted to the supporting frame, a stacker head carried by the stacker head lifting frame, means for rotating the stacker head frame about its pivot, a combined stop and pullback bar, means for attaching the lower end of said bar to the supporting frame, said means comprising a link having one end pivoted to the bar and the other pivoted to the supporting frame, means for guiding said stop and pullback bar, a stop for limiting its movement in one direction, means comprising a spring for producing a force for moving it against this stop and a stop for limiting the movement of the combined stop and pullback bar in the opposite direction.

3. An extension stacker comprising, in combination, a supporting frame, a two-part stacker frame, one end of one of said parts being pivotally attached to the supporting frame, a stacker head secured to one end of the other part, means for connecting said parts so that they may move longitudinally with respect to each other, means for rotating the stacker frame about its pivot, means for extending the stacker frame while it is rotated, a combined stop and pullback bar having its

lower end connected to the supporting frame by means of a link, one end of which is pivoted to the supporting frame and the other end of which is pivoted to the pullback bar, a stop for limiting the movement of the pullback bar towards the stacker frame, means comprising a spring for normally holding the pullback bar against the stop, a second stop for limiting the movement of the pullback bar against the force exerted by the spring and means carried by the stacker head extending means for engaging the pullback bar and for moving the lower end thereof about the stationary pivot of the connecting link.

4. An extension stacker comprising, in combination, a supporting frame, a stacker head lifting frame having one end pivotally connected with the supporting frame, a stacker head extension frame slidably connected with the lifting frame and located on top of the latter, means for holding the frames in parallel relation while permitting relative sliding movement between them, means for rotating the stacker head lifting frame, a pusher bar having one end pivoted to a stationary portion of the supporting frame at a point to the rear of and spaced from the point where the stacker frame is pivoted, a guide secured to the free end of the pusher bar, said guide extending downwardly along one side of the relatively movable parts of the stacker frame and slidable with respect to both frames and two spaced stops carried by the slidable part of the stacker frame, said guide having a portion extending across the underside of the stacker head lifting frame for holding the end of the pusher bar in a predetermined slid- 100
95
100
105

able relation with the stacker head lifting frame and the stacker head extension frame.

5. A stacker comprising, in combination, a supporting frame, a stacker head lifting frame having one end pivotally attached to the supporting frame, means for rotating the stacker head frame from a substantially horizontal to a substantially vertical position, a pull back device for imparting to the stacker head frame a force tending to return it to normal position, said pull back comprising a pull back bar whose lower end is connected to the frame by a movable link, said bar constituting a weight, a spring extending from the bar to the frame, and means for tensioning the spring and for raising the weight when the stacker head frame approaches vertical position.

6. A stacker having a supporting frame, a stacker head lifting frame pivoted at one end to the supporting frame, said stacker head lifting frame normally occupying a substantially horizontal position, and means for rotating the stacker head lifting frame from normal to a substantially vertical position, means for returning said lifting frame to normal position, said means comprising a pull 125
115
120
125
130

back bar having its lower end attached to the supporting frame by means of a link, a spring having one end attached to the supporting frame and the other end attached to the bar and means for raising the bar and stretching the spring when the stacker head is moved from normal to vertical position.

7. A stacker having a supporting frame, a stacker head lifting frame having one end pivoted to the supporting frame, an extension frame slidably supported on top of the lifting frame, a link having one end pivoted to the stacker frame at a point spaced from and above the lifting frame pivot, the free end of said link being slidably connected with the lifting frame, and means carried by the free end of the link and partly enclosing an arm of both frames for holding the end of the link against movement away from the arms while permitting it to slide along both arms when the lifting frame is moved about its pivot.

8. In an extension stacker having a supporting frame, a stacker head lifting frame pivotally attached at its rear end to the supporting frame and means for rotating the lifting frame about its pivot, an elongated wheel frame pivoted at its front end of each side member to the front end of the supporting frame, a wheel secured to each wheel frame, means pivotally attached to the rear end of each wheel frame for extending into the path of the lifting frame and latching means carried by the supporting frame.

9. A stacker having a supporting frame, a lifting frame pivoted at one end to the supporting frame, means for moving the lifting frame about its pivot, a link having its rear end pivotally attached to the supporting frame and means carried by the free end of the link for slidably attaching it to the lifting frame, said means comprising a guide member secured to the free end of the link and having a portion extending transversely across the lifting frame member on the side opposite from the free end of the link whereby by the link will be held against movement away from the lifting frame.

10. In an extension stacker having a supporting frame, a stacker head lifting frame pivotally attached at its rear end to the supporting frame, means for rotating the lifting frame about its pivot, a separate wheel frame pivoted at one end to each side of the supporting frame, a wheel pivoted to each frame intermediate its ends, and an arm pivotally attached to the free end of each wheel frame and adapted to be rotated about an axis parallel with the wheel frame whereby it may be turned so as to extend across the plane of the lifting frame member on the side to which the wheel frame is attached.

11. A stacker mechanism comprising, in combination, a supporting frame, having side members and end members, a post extending substantially perpendicularly to the plane

of the frame at each corner at one end, means for applying a force to each post tending to move it out of perpendicular position, and a brace extending from each corner post to the adjacent side member, the upper end of each brace being securely connected with the corner post, the lower end of each brace having a downwardly extending portion having a transverse shoulder on its front and rear side, the side member having a transverse notch adapted to receive the downwardly extending portion and means for securing the lower end of the brace to the side member.

12. A stacker device comprising a frame having a beam adapted to rest upon the ground, a substantially vertical corner post secured to one end of the beam, a brace (5) extending from near the upper end of the corner post to the beam, the beam having a transverse notch and the end of the brace (5) having a tenon adapted to fit the notch, a bolt passing through the end of the brace and through the beam straps (17) on each side of the tenon, the ends of said straps being joined by bolts extending through the beam and through the brace, a brace (27) between the first mentioned brace and the beam, the under side of the first mentioned brace (5) having a transverse notch for the reception of one end of the second brace, angle brackets located in the angles between the two braces, a bolt passing through one end of the angles and through the second brace (27), a plate (25) on the upper side of the first brace (5), bolts extending through the angle brackets, through the brace (5) and through the plate (25) the other end of the second brace having a tenon which extends into a transverse notch in the upper edge of the beam, a bolt extending through the lower end of the second brace and through the beam and plates (17) located on opposite sides of the second brace and the beam and secured to each other by bolts.

13. A stacker comprising a supporting frame, a lifting frame pivotally connected therewith, means for rotating the lifting frame about its pivots from a substantially horizontal to a substantially vertical position, a link having one end pivoted to the supporting frame at a point spaced from the pivot of the lifting frame, means for slidably connecting the free end of the link to an arm of the lifting frame, and a tension member for connecting the link with the supporting frame when the parts assume a predetermined position, said tension member being of such length that it prevents the link from moving to vertical position.

14. A stacker having a supporting frame, an extension lifting frame pivotally attached thereto, means for rotating the lifting frame from a substantially horizontal to a substantially vertical position, a stop means for limiting the rotation of the lifting frame in one

direction, said means including a tension bar connected with the supporting frame by means of a link and means for raising the tension bar when the lifting frame approaches the limits of its travel whereby the weight of the tension bar will assist in bringing the lifting frame to a stop and in returning the lifting frame.

15. A stacker having a supporting frame, an extension lifting frame pivotally attached thereto, means for rotating the lifting frame from a substantially horizontal to a substantially vertical position, stop means for limiting the rotation of the lifting frame in one direction, said means including a tension bar connected with the supporting frame by means of a link, a spring having one end connected with the tension bar and the other end connected with the supporting frame and means for lifting the tension bar and for increasing the tension in the spring as the lifting frame approaches the limits of its travel, whereby the force exerted by the spring and the weight of the tension bar will assist in bringing the lifting frame to a stop and in returning it.

16. A stacker having a supporting frame, an extension lifting frame pivotally attached thereto, means for rotating the lifting frame from a substantially horizontal to a substantially vertical position, stop means for limiting the rotation of the lifting frame in one direction, said means including a tension bar connected with the supporting frame by means of a link, a spring having one end connected with the tension bar and the other end connected with the supporting frame, and means for lifting the tension bar and for increasing the tension in the spring as the lifting frame approaches the limits of its travel, whereby the force exerted by the spring and the weight of the tension bar will assist in bringing the lifting frame to a stop and in returning it, said last named means including a link having one end pivoted to the supporting frame and the other end slidably connected with the stackerhead.

17. A stacker comprising a supporting frame, a stackerhead lifting frame having one end pivoted to the supporting frame and the other provided with a stackerhead, means for moving the frame from a substantially horizontal position through an angle of more than ninety degrees, a link having one end pivoted to the supporting frame at a point above and to the rear of the place where the lifting frame is pivoted, the free end of said link being slidably connected with the lifting frame, a cushion bar pivotally connected at its lower end to the supporting frame, means carried by the extension link for connecting it to the cushion bar when the link has been rotated through a given angle by the lifting frame, the distance from the pivot point of the cushion bar to the its point of

connection with the link being less than the distance between the pivots of the cushion bar and the link plus the distance from the pivot of the link to its point of attachment with the cushion bar, whereby a rigid structure is formed that serves as a stop for the stackerhead frame and in which the cushion bar is subjected to tension when the stackerhead lifting frame is stopped.

18. A stacker comprising a supporting frame, a stackerhead lifting frame having one end pivoted to the supporting frame and the other provided with a stackerhead, means for moving the frame from a substantially horizontal position through an angle of more than ninety degrees, a link having one end pivoted to the supporting frame at a point above and to the rear of the place where the lifting frame is pivoted, the free end of said link being slidably connected with the lifting frame, a cushion bar pivotally connected at its lower end to the supporting frame, means carried by the extension link for connecting it to the cushion bar when the link has been rotated through a given angle by the lifting frame, the distance from the pivot point of the cushion bar to its point of connection with the link being less than the distance between the pivots of the cushion bar and the link plus the distance from the pivot of the link to its point of attachment with the cushion bar whereby a rigid structure is formed that serves as a stop for the stackerhead frame and in which the cushion bar is subjected to a tension when the stackerhead lifting frame is stopped and resilient means connected with the cushion bar for producing a force tending to move it towards normal position.

19. A stacker comprising, in combination, a supporting frame, a stackerhead lifting frame having one end pivotally attached to the supporting frame and the other end provided with a stackerhead, means for rotating the stackerhead lifting frame from a substantially horizontal to a substantially vertical position and a combined stop and pull-back device, comprising a cushion bar having its lower end pivotally connected with the supporting frame by means of a short link, a spring having one end connected with the supporting frame and the other end connected with the cushion bar, said spring being under tension, a stop for limiting the movement of the bar in response to the action of the spring, a link pivoted to the frame above the pivotal connection of the cushion bar, means for slidably connecting the link with the stackerhead lifting frame whereby the link will be rotated about its pivot when the stackerhead frame is rotated and means for raising the cushion bar and for subjecting it to tension when the stackerhead frame has reached the limit of its movement whereby the further movement of the stackerhead frame will be resisted.

20. In a stacker, in combination, a supporting frame, a lifting frame having one end pivoted thereto, means for rotating the lifting frame about its pivots, a link having one end pivoted to the supporting frame and the other end slidably connected with the lifting frame, and means (77) for limiting the movement of the end of the link away from the lifting frame.
- 5 21. In a stacker, in combination, a supporting frame, a lifting frame having one end pivoted thereto, means for rotating the lifting frame about its pivots, a link having one end pivoted to the supporting frame and the other end slidably connected with the lifting frame, a hook member (76) carried by the link, said member having a portion extending along the side of the lifting frame and having its end projecting underneath the latter, and a guide member (78) secured to the other side of the link and extending downwardly along the other side of the lifting frame.
- 10 22. A stacker comprising, in combination, a supporting frame, an extension lifting frame pivoted to the supporting frame, means for rotating the stackerhead about its pivot from a substantially horizontal to a substantially vertical position, a link (73) pivoted to the supporting frame at a point spaced from the pivot of the lifting frame, the free end of the link being normally in contact with the lifting frame, and slideable therealong, means (76) for guiding the end 15 of the link as it moves along the lifting frame, and means (77) for holding the free end of the link against movement away from the frame.
- 20 23. In a stacker having, in combination, a supporting frame, a stacker head lifting frame pivoted to the supporting frame and means for rotating the stacker head about its pivot, a combined stop and pull back bar having its lower end attached to the supporting frame by means of a link that permits the bar to have a limited up and down movement and means made operative by the movement of the stackerhead lifting frame towards vertical position for raising the combined stop and pull back bar.
